UNITED STATES PATENT OFFICE.

FRITZ SAMUEL SVENSON, OF LUND, SKÅNE, SWEDEN.

LOCK.

SPECIFICATION forming part of Letters Patent No. 295,077, dated March 11, 1884.

Application filed October 15, 1883. (No model.)

To all whom it may concern:

Be it known that I, FRITZ SAMUEL SVENSON, doctor philosophiae, a subject of the King of Sweden, residing at Lund, in the Province of Skåne and Kingdom of Sweden, have invented certain new and useful Improvements in Locks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Figure 1 is a front view of a portion of a door provided with my improved spring-lock. Fig. 2 is a similar view with the lock-casing removed. Fig. 3 is a similar view with the lock removed, showing the manner of attaching the tumbler-case. Fig. 4 is a vertical section on line $a-a$, Fig. 1; and Fig. 5 is a perspective detail view of the tumbler-case and its fastening-nut.

Similar letters of reference indicate corresponding parts in all the figures.

My invention has relation to locks adapted to catch automatically when the door is closed; and it consists in the improved construction and combination of parts of a lock in which 30 a square bolt may be sprung forward in closing the door by the action of a beveled bolt striking a removable flange upon the catch-plate upon the door-frame, as hereinafter more fully described and claimed.

35 In the accompanying drawings, the letter A indicates the door, and B the frame, and the door has a shouldered perforation, C, near its latch edge, the inner portion of which, D, is larger in diameter than the outer, E. The 40 cylindrical tumbler-case F, which may contain tumblers of the Yale construction, or of any other suitable construction, fits into the outer portion of the bore in the door, and is provided upon its inner screw-threaded end, 45 G, with an annular nut, H, which bears against the shoulder formed by the larger portion of the perforation and secures the tumbler-case, which has the usual flange, I, at its outer end bearing against the outer side of the door in 50 the perforation. The inner end of the turn-

ing bolt in the tumbler-case, which bolt is lettered J, has a flat inwardly-projecting end, K, which, in case of a very thick door, is extended to form a flat connecting bar, and which projects into a transverse groove, L, in the stem M of the inner cam, N, of the lock, the casing O of which consists of an inner plate, P, bearing against the inner side of the door and forming the slotted front plate, Q, through which the bolts pass, and the outer flanged plate, R, which forms the protecting-casing for the lock mechanism, and has a number of screw-holes, S, corresponding to similar holes, T, in the inner plate, through which holes the securing-screws pass. The main bolt U, which is rectangular in cross-section at its outer end, 60 slides with that end in a slot, V, in the front plate of the casing and in a bearing, W, upon the inside of the inner plate with its inner portion, and is provided with a cross-piece or 65 yoke, X, upon its inner end, against the inner side of which the ends of the cams bear when they are operated, drawing the bolt back. A spiral spring, Y, bears with its one end against the bearing W, and with its other end against 70 the rectangular outer portion of the bolt, forcing the same out, and the inner portion of the rectangular portion of the bolt forms a shoulder, Z, upon its upper side, facing toward the front plate of the casing. A beveled catch, a, 75 bears against the upper side of the shoulder when the bolt is shot, and catches over the shoulder when the bolt is drawn in, and is secured upon the end of a flat spring, b, secured at its upper end to the inner plate of the lock-casing. An upright spring, c, is secured to the free end of the catch, and is provided with a similar catch, d, at its upper end, which catch is adapted to be engaged by the end of the vertical arm of a bell-crank, e, pivoted 80 upon the inner plate of the lock-casing and bearing with the end of its downwardly-pending arm against the inner end of the beveled spring-bolt f, which slides in a bearing, g, in the front plate of the casing above the main bolt. A knob, h, turns with its inner reduced end in a perforation in the outer flanged plate of the casing, and is provided upon the inner end, inside the casing, with a cam, i, which 90 serves to draw the bolt back, when it is turned, 95 too

bearing with one of its ends against the yoke or cross-piece of the main bolt. The catch-plate *j*, upon the inner edge of the door-frame, has an inwardly-projecting flange, *k*, having 5 two slots, *l* and *m*. Into the upper one, *l*, the main bolt fits, and a hook-shaped plate, *n*, is pivoted upon the plate near its upturned straight end *o*, which will, when the hook is turned with its straight portion in a horizontal position, form a continuation of the flange *k*, and be in position for the beveled end of the spring-bolt to strike it and be pushed in by it. When the hook is turned into a vertical position, the hooked end will pass through 15 the lower slot in the flange of the catch-plate into a slot, *p*, in the lower end of the front plate of the lock-casing, forming an extra bolt, which can only be operated from inside the door.

20. It will now be seen that when the main bolt is drawn back, either by the knob or by the key turning the tumbler-bolt, the catch will engage the shoulder upon the bolt and retain it. When the door now is closed and the bevelled end of the spring-bolt strikes the upturned end of the hook upon the catch-plate, the inner end of the spring-bolt will force the depending arm of the bell-crank back and the horizontal arm of the same will raise the upper catch, which will disengage the lower spring-catch, allowing the bolt to shoot out. In this manner the lock may be either used as a spring-latch or as a common bolt-lock by simply changing the position of the pivoted hook, and the hook may serve as an additional bolt for securing the door from the inside.

Having thus described my invention, I claim and desire to secure by Letters Patent of the United States—

40. 1. The combination of a main bolt in a lock having its outer end cut off square, actuated or shot by a spring, and having a shoulder facing outward, a spring-catch adapted to engage the shoulder upon the bolt when the lat-

ter is drawn back, and having an upright 45 spring-catch upon its upper side adapted to be engaged by the arm of a bell-crank, a bell-crank pivoted in the lock-casing, a beveled spring-bolt bearing with its inner end against the other arm of the bell-crank, and a catch-plate having a slot for the reception of the main bolt, and a removable flange adapted to be struck by the beveled spring-bolt, as and for the purpose shown and set forth. 50

2. The combination of a main bolt in a lock having means for drawing it back, and having a spring for shooting it, and having its outer end cut off square and an outwardly-facing shoulder upon its upper side, a beveled spring-catch adapted to engage the shoulder 60 when the bolt is drawn back, and having an upright spring provided with a beveled catch at its upper end, a bell-crank having one arm adapted to engage the catch upon the end of the upright spring, when the spring-catch engages the shoulder upon the bolt, a beveled spring-bolt bearing with its inner end against the other arm of the bell-crank, a catch-plate having a slot for the reception of the end of the main bolt and a slot below the same, and a 65 hook pivoted upon the inner side of the door-frame or the plane part of the catch-plate, having one end turned up to form a flange adapted to be brought in line with the slotted flange of the catch-plate, and to be struck by 70 the spring-bolt, and having its hooked end adapted to be turned down to pass through the lower slot in the flange of the catch-plate into a corresponding slot in the front plate of the lock-casing, as and for the purpose shown 75 and set forth. 80

In testimony whereof I affix my signature in presence of two witnesses.

FRITZ SAMUEL SVENSON.
